WIRE DRAWING MACHINE

Frank P. Dahlstrom, Woodbridge, Conn., assignor
to The Aetna-Standard Engineering Company,
Youngstown, Ohio, a corporation of Ohio

Application July 24, 1940, Serial No. 347,259

12 Claims.

(Cl. 205—14)

This invention relates to wire drawing machines and more particularly to continuous wire drawing machines in which in a single apparatus or machine the wire is drawn continuously through a series of reducing dies to effect a series of reductions in the size of the wire.

One type of continuous wire drawing machine which has been used extensively is exemplified by the machine disclosed in the Connor Patent No. 1,198,111, wherein a series of blocks or drums are provided which are driven at speeds to compensate approximately for the elongation of the wire in the successive drafts. In the machine of the Connor patent the drums are arranged to permit an accumulation of wire thereon to allow steady operation of the machine for some time, even though the speeds of the various drums are not in exact proportion to the elongation of the wire. It has been proposed, as disclosed in the application of Jerome R. George and Kenneth B. Lewis, Serial No. 281,666, filed June 28, 1939, to provide individual electric motor drives for the various blocks or drums in machines of the Connor type whereby the operator of the machine can control the speeds of the individual drums so that the machine can be regulated to maintain substantially constant accumulations of wire on the various drums, with the result that the machines can be operated continuously for indefinitely long periods of time without the necessity of running off the wire on the blocks and rethreading the machine at frequent intervals, as is required by the original Connor type of machine.

It is a general object of the present invention to provide a continuous wire drawing machine constituting a further improvement on machines of the type illustrated for example in the Connor patent and in which automatic means are provided for controlling the speed of the various drums of the machine so that the machine will be operated in such fashion that substantially equal weights of wire will be drawn through the dies associated with each block or unit for any given period of time. By this arrangement the accumulations of the wire on the blocks of the machine (except for the finishing block) remain substantially constant and the machine can be operated continuously with a minimum amount of attention being required.

Another object of my invention is to provide a simple and effective mechanism for automatically controlling the speed of the blocks of wire drawing machines. A further object is to provide an automatic control mechanism

which is simple and effective and substantially foolproof. Further objects and advantages of my invention will become apparent from the following description of a preferred form thereof, reference being made to the accompanying drawings. The essential characteristics are set forth in the claims.

Referring to the drawings, Fig. 1 illustrates a top plan view of a wire drawing machine embodying my invention and including three dies and associated blocks. Fig. 2 is a front elevation of the machine shown in Fig. 1. Fig. 3 is a sectional detail taken along the line of 3—3 in Fig. 1 but with the block rotated through 90° for convenience of illustration. Fig. 4 is a detail of part of the automatic control mechanism shown in Fig. 3, as indicated by the line 4—4 of Fig. 3, and Fig. 5 is a diagram of the electric circuits for the automatic control.

The machine illustrated in Figs. 1 and 2 may be of the general type described and claimed in my copending application Serial No. 285,338, filed July 19, 1939, and may be built up by assembling a number of generally similar units 10, 11 and 12, each unit being provided with die boxes indicated at 14, 15 and 16 for supporting suitable wire drawing dies 14a, 15a and 16a, and the units embodying blocks or drums 18, 19 and 20, respectively. The blocks or drums preferably are driven by independent variable speed motors 22, 23 and 24 through any convenient gearing or power transmitting mechanism such as that illustrated in my aforesaid application. Inasmuch as this mechanism and the mode of supporting the blocks on the frames of the units form, per se, no part of the present invention, no further description of these parts of the apparatus will be given in the present specification.

The units are arranged in line as shown in Figs. 1 and 2, the wire W being drawn through the die box 14 and its associated die 14a onto the drum or block 18 where it is wrapped tightly around the portion 26. As more wire is drawn on to the block, the coils are moved upwardly, surrounding the reduced portion 21. In threading the machine, a considerable number of turns of wire are accumulated on the block, so as to permit the wire to cool and rest between successive drafts. The wire is taken off the block in a generally axial direction over the sheave 28 carried by an arm 29 which is mounted for rotation about an axis aligned with the axis of the block 18 in a manner to be described in detail below. The wire is then carried upwardly and guided over the pulley 32 disposed above the

center of the drum 18, thence downwardly and around the pulley or sheave 33 to the die box 15 where it is drawn through another die on to the drum or block 19 of substantially identical construction with the block 18.

The wire is led away from the block 19 in the same manner as from the block 18, that is, it is carried over the pulley 34 supported by the arm 35, over pulleys 36 and 37 to the die box 16 and its associated die. The wire is drawn through the die box 16 and die 16a on to the finishing drum or block 20 which is of slightly different construction, in that it is provided with axially extending bars 38 for retaining a coil of wire of considerable size on the drum, the bars and coil being protected by a wire guard 39. The finishing unit is also preferably provided with an upwardly extending arm or bracket 40 adapted to support a hoist for removing the coil of wire from the finishing block.

In general, the three units may be of substantially identical construction so far as the supporting frames and driving mechanisms are concerned. The motors of units 16 and 19 are controlled by motor-driven rheostats 41 and 42, while a manually-operated rheostat 43 is provided for controlling the speed of the motor 24. Different gear ratios may be employed within the units as the drum of each succeeding unit must be operated at a higher rate of speed than the speed of the preceding unit due to the reduction and corresponding elongation of the wire as it passes through each succeeding die. The die box on the first unit 16 is arranged slightly differently than the die box on the remaining units and the finishing unit employs a block or drum of somewhat different character and the guide pulleys are eliminated from the finishing block. Generally speaking, however, the units preferably are of substantially identical construction, and as those skilled in the art will understand, it is not necessary to employ precisely three blocks or units, but the invention is useful in conjunction with a machine embodying only two blocks, as well as with a machine embodying more than three blocks. Further, the blocks need not be mounted on separate units, but may all be supported on a single bench or frame.

It is a characteristic of machines of this type that so long as wire is being removed from a block at the same rate at which it is being drawn on to the block, then the guide over which the wire is withdrawn from the block will remain stationary. That is, for example, if the relationship between the speeds of the blocks 18 and 19 and the diameters of the wire after it has been drawn through the dies 16a and 19a are such that the same weight of wire is drawn through both dies per unit of time, then the wire will be drawn on to the block 18 at precisely the same speed at which it leaves the block 18 over the sheave 28. Thus the same number of turns of wire will remain on the block 18, and the bracket 29 and the pulley 28 will remain stationary with respect to the central axis of the block.

If wire is being withdrawn from the block faster than it is being supplied thereto, then the number of turns of wire on the block will be reduced and the bracket 29 and pulley 28 will rotate around the central axis of the block in a direction opposite to the rotation of the block, that is, in the drawings the block 18 is driven in a counter-clockwise direction and under these circumstances the guide pulley 28 will swing

around in a clockwise direction. On the other hand if the wire is being removed from the block at a slower rate than it is being drawn on to the block and accordingly, wire is being accumulated on the block, then the guide pulley 28 and bracket 29 will swing around the central axis of the block in the same direction as the direction of rotation of the block but at a slower speed.

I employ this characteristic motion of the guide over which the wire is withdrawn from the blocks to actuate the automatic control mechanism for the speed of the motors driving the various blocks. That is, through a mechanism to be described in detail below, the rheostats 41 and 42, which control the motors 22 and 23 respectively, are automatically adjusted in response to movements of the pulleys 28 and 34, associated with the blocks 18 and 19 respectively, to control the speeds of the motors so that under ordinary operating conditions substantially the same number of turns of wire will remain on the blocks 18 and 19 at all times, the motor driving either block being automatically adjusted with respect to the rate at which the wire is withdrawn to a succeeding block to insure that the wire is drawn on to and removed from the blocks at substantially the same speed.

In the embodiment shown in the drawings, the speed of the finishing block may be manually adjusted to a given value. Then the speed of the motor 23 will be automatically adjusted so that the block 19 will function to draw the wire through the die 15a at substantially the same speed that the wire is removed from the block 18 to the die 16a and the finishing block 20. Similarly, the speed of motor 22 will be automatically adjusted so that the block 18 will be driven at such a speed, depending upon the reduction effected by the die 16a, that the wire will be drawn through the die 16a and on to the block 18 at substantially the same speed that it is removed from that block to supply wire to the die 15a as demanded by the operation of the block 19.

A preferred form of automatic mechanism for so adjusting the speeds of the motors and blocks is illustrated in the drawings. The mechanism associated with unit 18 will be described, it being understood that the control mechanism is preferably identical for units 16 and 19, or, in a machine embodying more than three blocks, for all blocks except the finishing block.

As shown in Fig. 3, the pulley 28 is supported by a bracket 29 which in turn is secured to an annular flange 45 extending from a hub 46. The hub is supported by suitable bearings 47 upon the upwardly extending shaft 48 which is rigidly mounted upon the block 18 and is coaxial therewith. Thus the bracket 29 and pulley 28 are free to swing around the shaft 48 and the pulley can properly guide the wire being withdrawn from the block regardless of any variation in rate of operation of the machine.

To tension properly the wire as it is being withdrawn from the block and to urge constantly the pulley into engagement with the wire, I preferably employ a friction drive which tends to rotate the hub and pulley in the direction of rotation of the block. This may comprise an annular plate 50 having an annular disk 51 of suitable friction material secured thereto, the friction material engaging the flat annular surface 52 formed on the upper part of the block 18. The annular plate 50 has a threaded substantially cylindrical portion 53 extending upwardly

therefrom, the internal threads on the cylindrical portion engaging external threads formed on the hub member 46, as indicated at 54. The driving engagement between the annular member 50 and the hub 46 is through the coil spring 55 which surrounds the cylindrical portion 53, one end of the spring engaging the screw 56 mounted on the annular flange 50 while the other end of the spring engages one of the series of pins 57, disposed in openings 58 in the upper flange 45.

By engaging the end 59 of the spring with different pins, the force exerted by the spring may be adjusted and correspondingly the frictional engagement between the friction material 51 and the surface 52 may be varied by the adjustment of the spring. The arrangement is such that the action of the spring between the pin 57 and the screw 56 tends to rotate the threaded sleeve 53 with respect to the threaded hub 46 in a direction to urge the friction material downwardly into engagement with the surface 52, that is, looking down on the embodiment illustrated, if the pulley and flange are held stationary by the wire, the spring tends to rotate member 50 in a clockwise direction; however, this action is opposed by the counterclockwise rotation of the drum, which, through the friction material 51, tends to rotate the member 50 in counter-clockwise direction and thus to reduce the pressure of the friction material against the surface 53. Thus the friction drive is dependent on the adjustment of the spring and is independent of the coefficient of friction of the friction material against the surface 52, with the result that the drive is automatically balanced in operation to maintain a tension in the wire proportional to the torque exerted by the spring between the members 50 and 45. By this means the force tending to rotate the upper flange 45 and thus to swing the pulley about the axis of the block, and correspondingly the tension on the wire can be accurately controlled. In order to make for easy adjustment of the spring, the end engaging the pin 57 is preferably extended outwardly beyond the limits of the flange 45, to provide a convenient handle.

By this construction a simple and effective friction drive is provided, whereby the pulley 28 is always urged to rotate in a direction of rotation of the block or drum 18, but whereby slippage can take place between the parts whenever the tension on the wire engaging the pulley exceeds a predetermined amount, which may be adjusted by the adjustment of the spring 55. The tension on the wire is kept substantially constant for any given adjustment and any difference in the relative speeds at which the wire is being drawn on to and withdrawn from the block is promptly reflected by rotation of the flange 45 and the swinging of the pulley 28 about the axis of the block. In the apparatus shown in the drawings, the pulley and flange will move in a clockwise direction when the block is running too slowly and move in a counter-clockwise direction when the block is running too fast (accumulating wire) with relation to the rate at which the wire is being withdrawn therefrom.

The rotation of the flange and pulley is utilized to control the speed of the motor 22 so that the block 18 will be driven at the proper speed with respect to the speed of the succeeding block 19 so that the accumulation of wire on the block 18 will remain substantially constant. This is accomplished by connections between the flange 45 and the controls for the motor 22 whereby the

speed of the motor 22 is increased when the flange rotates in a clockwise direction and decreased when the flange rotates in a counter-clockwise direction. Any suitable mechanism may be employed for effecting this result, a preferred form of mechanism comprising the motor driven rheostat 41 which controls the field current of the motor 22 and which in turn is controlled by the switches 61 and 62. These switches are operated by cams 63 and 64 engaging the switch levers 65 and 66, the cams being mounted upon a shaft 67 supported by a suitable bearing 68 preferably mounted on the upright plate 69 forming part of the frame of the unit. The shaft is rotated, either to leave both switches in the off position or to close one or the other, by means of a lever 71 supported on pins 72 and 73 which are carried by the collar 74 keyed to the shaft 67.

The lever extends downwardly and engages the peripheral edge of a ring 75 mounted upon the flange 45 and rotatable therewith. Rotation of the flange 45 will thus result in the rotation of the ring 75 which by frictional engagement will cause the lever 71 to swing in one direction or the other depending upon the direction of rotation of the flange and ring. The lever is urged into frictional engagement with the ring by the spring 76 acting between the upper end of the lever 71 and the washer 77 mounted on the upper pin 73. The compression of the spring may be regulated by adjusting the position of the washer on the pin. By this arrangement the lever 71 and the switches 61 and 62 may be actuated immediately in response to movement of the flange 45 and ring 75, but continued rotation of the ring can have no damaging effect and will result in only slight wear, for the construction is such that as the lever 71 is swung from its vertical position towards the extreme positions indicated in broken lines at a—a in Fig. 4, the pressure of the lever against the ring is gradually reduced until in the extreme positions the pressure may be very slight.

The electrical connections are illustrated diagrammatically in Fig. 5 where it will be seen that swinging the lever 71 to the left in response to rotation of the ring 75 in counter-clockwise direction, for example, will result in closing the circuit through the switch 62. When this circuit is closed, current will flow from the direct current supply main 79 through the conductor 81, limit switch 82, switch 62, the field coil 85 of the rheostat motor 86 and thence through the armature of the rheostat motor to the direct current supply line 80. This will result in the operation of the rheostat motor 85 in a direction to decrease the speed of the main driving motor 22, the arm 88 of the rheostat 41 being swung in a direction to decrease the resistance in the field circuit of the motor 22 and thus decrease its speed. Likewise if the lever 71 is swung to the right in response to clockwise rotation of the ring 75, the circuit will be completed through the switch 61 and limit switch 83 (shown in open position in Fig. 5) which will result in the energization of the field 87 of the rheostat motor 85, this field coil being wound to operate the motor in the opposite direction and thereby drive the rheostat to increase the field resistance of the main driving motor 22 and correspondingly increase the speed of the motor and of the drum 18.

The limit switches 82 and 83 operate to protect the rheostat, these switches being arranged so that the circuit from the direct current supply main to the rheostat motor will be opened when

the rheostat comes to the end of its travel. This is accomplished by an extension on the rheostat arm 88 which engages the switches in the extreme positions of the arm. In the diagram shown the rheostat is at the position for the highest speed of operation of the motor 22, the circuit being from the D. C. supply line through the conductor 81 and all of the resistance of the rheostat to the rheostat arm 88 and from the arm through the conductor 90 and the field 81 of the motor 22 back to the supply line 80. The arm 88 has opened switch 83 and stopped further operation of the rheostat motor in that direction, although the motor is ready for operation in response to closing of switch 62, to decrease the speed of motor 22. Thus no damage can take place to the rheostat or the associated mechanism even though the friction ring 75 should continue to rotate in the same direction for a considerable length of time. This action may occur under various conditions of operation of the machine, particularly when the machine is being threaded and put into operation.

As stated above, the automatic control mechanisms for units 10 and 11 and their associated blocks 18 and 19 are substantially identical. Those skilled in the art will appreciate that an automatic control mechanism is not required for the finishing block 20, a manual control for the motor 24 driving this block preferably being provided. This control may comprise a rotatable control knob 92 secured to a shaft 93 extending to the rear of the unit where it is provided with a sprocket 94 connected by a chain 95 to a sprocket 96 mounted on the shaft of the hand operated rheostat 43. Thus the rheostat 43 and the speed of the motor 24 may be conveniently controlled by the operator merely by operation of the knob 92. To give the operator an indication of the position of the rheostat and the speed of operation of the motor, the rheostat shaft is extended through the plate 97 and is provided with a pointer 98 which in conjunction with the dial 99 carried by the plate 97 indicates to the operator the position of the rheostat.

Each of the units is provided with manual means such as conventional push-button switches (not shown) for starting and stopping the respective motors and preferably the switches are arranged to operate the motors either at a slow speed for threading or at normal speed, in which latter case the speed of the motors is controlled by the respective rheostats associated therewith. These controls may be of any well-known type. In addition to the push-button control the units are preferably provided with bars 101, 102 and 103 respectively which are connected with switch mechanisms of any convenient type so that a push on any one of the bars will result in the stopping of the entire machine.

In operation the machine is threaded in the usual manner, that is, the wire or rod to be drawn, with a suitable point formed thereon, is first inserted through the die 14a, then by means of the usual tongs, is drawn around the drum 18 until the frictional engagement between the drum and the wire is sufficient to pull the wire through the die. The tongs are then removed and the desired number of turns are accumulated on the block 18. The wire is then led around the pulleys 28, 32 and 33, threaded through the die 15a and wound on the drum 19. The threading operations initially are carried out at slow speed of the motors, but if desired, the automatic control mechanism associated with the block 18

may be used to correlate the speed of that block with the speed of operation of the succeeding block 19.

The wire leaves the block 19 over pulleys 34, 36 and 37 and is led through the finishing die 16a to the finishing block 20. As soon as sufficient wire has been accumulated on the finishing block 20 to give sufficient frictional engagement between the block and the wire to permit the wire to be drawn through the finishing die, the tongs can be removed and the operation of the machine can be completely automatic. All of the motors are then put on their normal speed operation. The speed of the finishing block is manually adjusted to the desired rate by means of the control knob, and by means of the automatic mechanisms heretofore described, the speeds of the blocks 19 and 18 are automatically correlated with the speed of the finishing block, the ultimate speeds of these blocks depending upon the relationship between the various diameters of the wire as it is drawn through the several dies.

In use, the automatic speed adjustment functions to bring the motors to proper speed a short time after the machine has been threaded and is operating normally. In long runs, the adjustments of the rheostats will automatically change in response to changes in elongation occasioned by wear of the dies or changes in the characteristics of the material. However, these factors are all taken care of automatically as the need for adjustment arises. Accordingly, the machine may be operated for long periods of time so long as a continuous supply of wire is available to the first unit.

The automatic speed control of the machine increases the rate of production, and improves the efficiency of power utilization. The machine is also advantageous in that time is given between the successive drawing operations to permit the wire to cool and rest, which gives improved results, particularly with some types of alloys.

The foregoing description of a preferred form of my invention is given by way of example, it being evident that various changes and modifications in the preferred form described herein can be made by persons skilled in the art without departing from the spirit and teachings of my invention. Therefore, it is to be understood that my patent is not limited to the preferred embodiment described herein or in any manner other than by the scope of the appended claims when given the range of equivalents to which my patent may be entitled.

I claim:

1. In a continuous wire drawing machine comprising a plurality of dies, a plurality of blocks for drawing wire through said dies, said blocks being adapted to carry a reserve or accumulation of wire thereon, and means for withdrawing the wire from at least one of said blocks in an axial direction including a guide for said wire rotatable about an axis substantially coaxial with said block, the combination of friction means tending to rotate said guide in the direction of rotation of said block, the tension of the wire against guide tending to rotate said guide in the opposite direction, and means controlled by the rotation of said guide for controlling the speed of said block to maintain the accumulation of wire thereon substantially constant.
2. In a continuous wire drawing machine comprising a plurality of dies, a plurality of blocks for drawing wire through said dies, said blocks

being adapted to carry a reserve or accumulation of wire thereon, the combination of means for withdrawing the wire from at least one of said blocks in an axial direction including a guide for said wire rotatable about an axis substantially coaxial with said block in response to variations in the rates at which wire is being drawn onto and withdrawn from said block and means controlled by the rotation of said guide for controlling the speed of said block to maintain the accumulation of wire thereon substantially constant.

3. A continuous wire drawing machine comprising a plurality of dies, a plurality of blocks for drawing wire through said dies, said blocks being adapted to carry a reserve or accumulation of wire thereon, means for withdrawing the wire from said blocks in an axial direction including a pulley for guiding said wire, said pulley being swingable about an axis substantially coaxial with said block, friction means tending to swing said pulley in the direction of rotation of said block, the tension of the wire against said pulley tending to swing said pulley in the opposite direction, and means controlled by the swinging movement of said pulley for controlling the speed of said block to maintain the accumulation of wire thereon substantially constant.

4. In a continuous wire drawing machine of the type in which wire may be withdrawn from a block at a speed different from that at which the wire is being drawn on to the block, a plurality of wire drawing blocks, at least one of said blocks having independently adjustable means for driving said block and means automatically controlled by variations in the speed at which wire is withdrawn from said block as compared to the speed at which wire is being drawn on to said block for controlling the speed of said block so that the speed at which wire is withdrawn from said block will be substantially equal to the speed at which wire is being drawn on to said block and the accumulation of wire thereon will be substantially constant.

5. A continuous wire drawing machine comprising a finishing block, a die associated therewith, means for driving said finishing block, manually operable means for adjusting the speed of said driving means, another block preceding said finishing block, a die associated therewith, said other block being arranged to retain an accumulation or reserve of wire thereon, independently variable speed means for driving said other block, means for withdrawing wire from said other block in an axial direction and guiding the wire to said finishing block whereby the rate of withdrawal of wire from said other block depends upon the speed of operation of said finishing block and the reduction effected by the die associated therewith, and means associated with said other block and controlled by variations in the speed at which wire is withdrawn therefrom as compared to the speed at which wire is drawn onto said block for automatically adjusting the speed thereof to maintain the accumulation or reserve of wire thereon substantially constant in normal operation of the machine, regardless of normal variations in the speed of said finishing block or normal changes in the reduction effected by the dies.

6. In a wire drawing machine, a block for drawing wire through a die, a driving motor for said block, a motor driven rheostat for controlling the speed of said driving motor, a flanged member rotatably mounted upon a bearing carried by

said block and coaxial therewith, friction means tending to rotate said member with said block, a guide pulley for wire withdrawn from said block mounted on said member and arranged so that engagement of the wire against the pulley tends to prevent rotation of said member and switch means actuated by said flanged member whereby rotation of said member will result in operation of said motor driven rheostat and adjustment of the speed of said driving motor.

7. In a wire drawing machine, a block for drawing wire through a die, a driving motor for said block, an electrically operated rheostat for controlling the speed of said driving motor, a member mounted for rotation with respect to said block and coaxial therewith, means tending to rotate said member with said block, a guide for wire withdrawn from said block mounted on said member and arranged so that engagement of the wire with said guide controls the rotation of said member, switch means actuated by said member, and electrical connections between said switch means and said rheostat whereby rotation of said member will result in operation of said rheostat and adjustment of the speed of said driving motor, and a slip connection between said member and said switch means.

8. In a wire drawing machine having a frame structure, a block for drawing wire through a die, and a driving motor for said block, the combination of an electrically operated rheostat for controlling the speed of said driving motor, a flanged member rotatably mounted upon a bearing carried by said block and coaxial therewith, friction means tending to rotate said member with said block, a guide pulley for wire withdrawn from said block mounted on said member and arranged so that engagement of the wire against the pulley tends to prevent rotation of said member, a ring rigidly mounted on and surrounding said flanged member and rotatable therewith, a lever pivotally mounted on said frame structure and frictionally engaging said ring in a region spaced from said pivotal mounting whereby rotation of said ring will result in a swinging movement of said lever in one direction or the other, depending on the direction of rotation of said ring, switch means actuated by said lever and electrical connections between said switch means and said rheostat whereby rotation of said ring and flanged member will result in operation of said rheostat and in increasing or decreasing the speed of said driving motor, depending on the direction of rotation of said ring.

9. In a wire drawing machine having a frame structure, a block for drawing wire through a die, and a driving motor for said block, the combination of an electrically operated rheostat for controlling the speed of said driving motor, a guide for wire withdrawn from said block mounted for rotation about the axis of said block, the movement of said guide depending upon the relative rates at which wire is being drawn onto and withdrawn from said block, switch means actuated by movement of said guide, there being a friction connection between said switch means and said guide and electrical connections between said switch means and said rheostat whereby movement of said guide will result in operation of said rheostat and in increasing or decreasing the speed of said driving motor, depending on the direction of movement of said guide.

10. In a wire drawing machine having a frame structure, a block for drawing wire through a die,

and a driving motor for said block, the combination of an electrically operated rheostat for controlling the speed of said driving motor, a guide for wire withdrawn from said block mounted for rotation about the axis of said block, the movement of said guide depending upon the relative rates at which wire is being drawn onto and withdrawn from said block, a ring concentric with said block and rotatable with said guide, a lever pivotally mounted on said frame structure and frictionally engaging said ring in a region spaced from said pivotal mounting whereby rotation of said ring will result in a swinging movement of said lever in one direction or the other, depending on the direction of rotation of said ring, switch means actuated by said lever and electrical connections between said switch means and said rheostat whereby rotation of said ring and flanged member will result in operation of said rheostat and in increasing or decreasing the speed of said driving motor, depending on the direction of rotation of said ring.

11. In a wire drawing machine a block for drawing wire through a die, driving means for said block, a flanged member rotatably mounted upon a bearing carried by said block and coaxial therewith, friction means tending to rotate said member with said block, an adjustable spring for

driving said member from said friction means and for urging said friction means into engagement with said block, and a guide pulley for wire withdrawn from said block mounted on said member and arranged so that engagement of the wire against the pulley tends to prevent rotation of said member and to oppose the action of the spring and thereby tends to reduce the pressure of said friction means against said block, whereby the tension of said wire may be controlled by adjusting said spring.

12. In a wire drawing machine having a frame structure, a block for drawing wire through a die, and a driving motor for said block, the combination of a rheostat for controlling the speed of said driving motor, a guide for wire withdrawn from said block mounted for movement about the axis of said block, the movement of said guide depending upon the relative rates at which wire is being drawn onto and withdrawn from said block, a ring concentric with said block and rotatable with said guide, means frictionally engaging said ring for controlling said rheostat whereby rotation of said ring will result in operation of said rheostat and in increasing or decreasing the speed of said driving motor, depending on the direction of rotation of said ring.

FRANK P. DAHLSTROM.
